DESIGN FOR A HANDBAG

Aaron Landis, Elizabeth, N. J.

Application April 22, 1937, Serial No. 68,924

Term of patent 3½ years

To all whom it may concern:

Be it known that I, Aaron Landis, a citizen of the United States and resident of Elizabeth, in the county of Union and State of New Jersey, have invented a new, original, and ornamental Design for Handbags, of which the following is a specification, reference being had to the accompanying drawing, forming a part thereof, and of which Figure 1 is a view in front elevation; Fig. 2 is an end view, and Fig. 3 is a view in rear elevation, of a handbag showing my new design.

The characteristic features of my design reside in the envelope type of handbag having a bag body and closure flap consisting of woven celluloid fabric and in the continuous strip-like border portion forming a panel effect for the bag body and closure flap.

I claim:

The ornamental design for a handbag substantially as shown and described.

AARON LANDIS.
